UNITED STATES PATENT OFFICE.

LEON TREBOUL, OF NEW YORK, N. Y.

WRENCH.

1,163,185.

Specification of Letters Patent.

Patented Dec. 7, 1915.

Application filed October 6, 1915. Serial No. 54,326.

To all whom it may concern:

Be it known that I, LEON TREBOUL, a citizen of the United States, residing at New York city, in the county of New York and State of New York, have invented certain new and useful Improvements in Wrenches, fully described and represented in the following specification and the accompanying drawings, forming a part of the same.

10 My invention relates to wrenches and more particularly to a type thereof having rigid jaws.

15 In wrenches of the alligator and other types, it is desirable to employ a toothed jaw removably mounted in the wrench head so that this jaw may be properly cut and hardened independently of and be conveniently assembled with other parts of the wrench 20 and removed and replaced as desired.

25 Various types of wrenches having removable jaws of this character, have been heretofore devised, and it is not my intention in this application to claim broadly a wrench embodying therein a removable jaw, but rather an improved construction of wrench the head of which is so constructed as to permit the application thereto of a removable alligator jaw, or of any other 30 special type of jaw, or other gripping surface, of the spanner type, and the head and removable jaw of which are so shaped as to secure the desired ready and firm attachment of the jaw combined with a comparatively low manufacturing cost.

35 A wrench made in accordance with my invention is so constructed as to cause the transmission of the stresses upon the jaws directly to the wrench head, means being provided whereby the removable jaw is so secured in relation to the wrench head as to secure absolute rigidity of the parts when assembled, and avoid likelihood of displacement of the movable jaw while the wrench 40 is in use. When a toothed jaw is mounted in the wrench head to produce an alligator wrench, and the construction is particularly adapted for use with this type of jaw, the opposed divergent coöoperating faces of the 45 jaws are best so arranged with relation to the point of application of the force to the wrench handle, as to secure the maximum gripping effect and minimize likelihood of the wrench slipping from the pipe or other 50 object to which it is applied. Furthermore, the wrench is so constructed as to permit the

rapid assembling of the removable jaw in the head, the locking means for securing the jaw in position being adapted to firmly wedge the jaw in place. I also so construct 60 the wrench head, that in the event of the binding of the removable jaw therein, force may be conveniently applied to the jaw to overcome this binding, and facilitate the separation of the jaw from the head. 65

The invention consists in the novel features of construction and combination of parts hereinafter set forth and described and more particularly pointed out in the claims hereto appended.

70 Referring to the drawings:—Figure 1 is a top view of a wrench embodying my invention; Fig. 2 is a side view thereof; Fig. 3 is a section on the line 3—3 of Fig. 2; Fig. 4 is a side elevation of the wrench 75 showing the jaw removed from the head; Fig. 5 is a side view of a wrench showing the application thereto of an attachment whereby a spanner wrench may be formed in lieu of an alligator wrench; and Fig. 6 80 is a view of a supplemental, removable jaw by means of which a spanner wrench adapted to different sizes of the nut may be produced.

85 In the embodiment of my invention shown in the drawings, *a* indicates a wrench handle, carrying a head *b* preferably formed integrally therewith. Carried by the said head *b* is a fixed jaw *c* extending at an angle to the axis of said handle. Also carried by or forming part of the head *b* is an 90 angular jaw stump *d* extending at an angle to the jaw *c* and at an angle to the axis of the handle *a* and on the same side thereof as the jaw *c*. The stump *d* is provided with 95 angularly arranged bearing surfaces *d'*—*d*², and extending from the surface *d*² toward the jaw *c* is a bearing surface *b'* on a plane substantially parallel with the surface *d*'. The head *b* is provided with a socket *b*² 100 opening into the bearing surface *b'* and extending to substantially the same angle as the bearing surface *d*². Said socket *b*² is preferably slightly tapered.

105 Extending transversely through the head *b*, is an opening *e*, projecting into the end of the socket *b*² and between said opening *e* and the bearing surface *b'* is a second opening *f* extending transversely through said head, and projecting into the side of said 110 socket *b*².

In the preferred form of the invention,

I provide a jaw g having a toothed face g' and provided with a top recess forming angularly arranged shoulders g^2-g^3 adapted respectively to engage the bearing surface 5 d' and d^2 , upon the jaw stump d and forming therewith one jaw of the wrench. The end of the jaw g is provided with a tapered shank h adapted to fit the socket b^2 , said shank having therein a side opening h' 10 adapted to register with the opening f in the head b . The end of the jaw g adjacent the shank h is finished to form a surface g^4 adapted to engage the bearing surface b' on the head b .

15 To relieve the shank h of excessive stresses, I provide interlocking means between the shoulder g^2 and the bearing surface d' , said means preferably comprising a stud d^4 carried by the jaw stump d and 20 entering a socket g^5 in the removable jaw g . The said jaw g is held rigidly in position with relation to the head b by means of a pin i extending through the opening f in the said head b and the opening h' in the 25 shank h . By using a tapered pin, I secure a wedging action upon the shank h which will draw the shoulders g^2-g^4 firmly against the surfaces d' and b' and at the same time force the shoulder g^3 firmly against the shoulder d^2 .

When the jaw g is in position, the end of the shank h will project into the opening e to an extent to permit the insertion of any suitable implement through the said opening, into engagement with the end of the shank h in a manner to permit the application of sufficient force to said shank to thrust it outwardly of the socket b^2 .

It will be observed that in the assembled 40 tool shown, both jaws c and g , which extend at an acute angle to each other, will lie below the axis of the handle, or below a straight line drawn through the point of application of force and the center of the 45 head. This arrangement insures the maximum gripping moment of the jaw g upon the pipe or other object to which the wrench is applied.

In the form of the invention shown in 50 Figs. 5 and 6, the construction is the same as that heretofore described with the exception that instead of using an alligator or pipe jaw g , I use a jaw j having an opening therein adapted with the jaw c to form 55 the rectangular opening of an ordinary spanner wrench. To permit variance in the size of the opening in the spanner wrench, I provide the jaw j with a socket j' adapted to receive a stud h' carried by a supplemental jaw k also having a rectangular opening 60 therein. By using supplemental jaws having different sized openings, another such jaw k^2 being illustrated in Fig. 6, a variety of different sized spanner wrenches 65 may be embodied in a single wrench struc-

ture. The jaw j is provided with angularly arranged shoulders j^2 and j^3 adapted to co-operate with the bearing surfaces $d'-d^2$ and a shoulder j^4 adapted to bear upon the bearing surface b' .

It will be observed that by reason of the arrangement of the bearing surface $d'-d^2$ and b' and the co-operating shoulders g^2, g^3, g^4 , or j^2, j^3, j^4 , the jaw g or j will be held with relation to the jaw stump d in a manner to insure such rigidity between these parts as to form practically an integral structure. By utilizing the shank h and the pin i passing through the openings f and h' the said shoulders and bearing surfaces may 80 be drawn tightly together. The opening e allows the application of force to the shank h in a manner to insure its loosening to an extent to permit the jaw to be readily removed. By tapering the shank h and socket b^2 , the convenient removal of the jaw is 85 facilitated, and a tight binding action of the shank h with the socket b^2 in applying the jaws is secured.

It will be seen that the formation of the 90 engaging portions of the head and removable jaw of the wrench as shown involves no expensive machine work, the shank h and stud d^4 and the sockets b^2 and g^5 being round in cross-section, and all the other 95 meeting surfaces being flat or plane surfaces extending the full width of the wrench head and jaw.

While in the accompanying drawings the handle a is shown as being straight and elliptical in cross-section, the form of the handle is immaterial to the invention so long as the handle grip thereof is so located as to secure the desired angularity in the direction of projection of the jaws of the 105 wrench with relation to the handle.

What is claimed is:

1. A wrench embodying therein a handle, a head carried thereby, a fixed jaw carried by said head, a jaw stump also carried by 110 said head and provided with an end bearing surface and a bearing surface presented toward said fixed jaw, said head having a bearing surface between said stump and said fixed jaw, a removable jaw recessed to form shoulders adapted to bear against the bearing surfaces on said stump, and co-operating means carried by said removable jaw and said head respectively whereby said removable jaw may be rigidly secured in relation to said head and said jaw stump, one end of 115 said removable jaw being adapted to bear against the bearing surface on said head.

2. A wrench embodying therein a handle, a head carried thereby, a fixed jaw carried by said head, a jaw stump also carried by 120 said head provided with an end bearing surface and a bearing surface presented toward said fixed jaw, said head having a bearing surface between said stump and said fixed 125

- jaw, a socket opening outwardly through the last said bearing surface and an opening extending transversely therethrough and projecting into said socket, a removable jaw recessed to form shoulders adapted to bear against the bearing surfaces on said stump, a shank carried by said removable jaw having a cut-out portion adapted to register with said transverse opening and adapted to enter said socket, and a pin adapted to enter said transverse opening and the cut-out portion of said shank, said removable jaw adjacent said shank being adapted to bear against the bearing surface on said head.
3. A wrench embodying therein a handle, a head carried thereby, a fixed jaw carried by said head, a jaw stump also carried by said head provided with an end bearing surface and a bearing surface presented toward said fixed jaw, said head having a bearing surface between said stump and said fixed jaw, a socket opening outwardly through the last said bearing surface and an opening extending transversely therethrough and projecting into said socket, a removable jaw recessed to form shoulders adapted to bear against the bearing surfaces on said stump, a coöperating stud and socket upon said stump and said removable jaw respectively, a shank carried by said removable jaw having a cut-out portion adapted to register with said transverse opening and adapted to enter said socket, and a pin adapted to enter said transverse opening and the cut-out portion of said shank, said removable jaw adjacent said shank being adapted to bear against the bearing surface on said head.
4. A wrench embodying therein a handle, a head carried thereby, a fixed jaw carried by said head, a jaw stump also carried by said head provided with an end bearing surface and a bearing surface presented toward said fixed jaw, said head having a bearing surface between said stump and said fixed jaw, a socket opening outwardly through the last said bearing surface and an opening extending transversely therethrough and
- projecting into said socket, a removable jaw recessed to form shoulders adapted to bear against the bearing surfaces on said stump, a shank carried by said removable jaw having a cut-out portion adapted to register with said transverse opening and adapted to enter said socket, and a pin adapted to enter said transverse opening and the cut-out portion of said shank, said removable jaw adjacent said shank being adapted to bear against the bearing surface on said head, said head having a second opening transversely therethrough and projecting across the bottom of said socket.
5. A wrench embodying therein a handle, a head carried thereby, a fixed jaw carried by said head, a jaw stump also carried by said head provided with an end bearing surface and a bearing surface presented toward said fixed jaw, said head having a bearing surface between said stump and said fixed jaw, a socket opening outwardly through said bearing surface and an opening extending transversely therethrough and projecting into said socket, a removable jaw recessed to form shoulders adapted to bear against the bearing surfaces on said stump, a coöperating stud and socket upon said stump and said removable jaw respectively, a shank carried by said removable jaw having a cut-out portion adapted to register with said transverse opening and adapted to enter said socket, and a pin adapted to enter said transverse opening and the cut-out portion of said shank, said removable jaw adjacent said shank being adapted to bear against the bearing surface on said head, said head having a second opening transversely therethrough and projecting across the bottom of said socket.
- In testimony whereof I have hereunto set my hand in the presence of two subscribing witnesses.
